UNITED STATES PATENT OFFICE

GEORGE A. STACKHOUSE, OF OAKLAND, CALIFORNIA, ASSIGNOR TO L. A. YOUNG
SPRING & WIRE CORPORATION, OF DETROIT, MICHIGAN

METHOD OF ASSEMBLING BED AND CUSHION SPRINGS

Application filed April 14, 1930. Serial No. 443,948.

The main objects of this invention are to provide a method of assembling helically coiled springs with a supporting base and center tie which enables very rapid assembling and also results in a very stable and effective support for the springs.

Objects relating to details and economies of my invention will appear from the description to follow. The invention is defined and 10 pointed out in the claims.

A structure which is a preferred embodiment of my invention is illustrated in the accompanying drawings, in which:

Fig. 1 is a fragmentary sectional view of a 15 bed spring assembled by my improved method.

Fig. 2 is an enlarged fragmentary section on line 2-2 of Fig. 1.

Fig. 3 is a fragmentary plan view, the base 20 unit being omitted.

Fig. 4 is a fragmentary perspective view illustrating the initial or first step in the assembling of the springs.

Fig. 5 is a fragmentary view illustrating 25 the second step, and

Fig. 6 is a fragmentary view illustrating the third or final step.

The spring structure assembled by my method comprises a base unit consisting of 30 side rails 1, cross bars 2 disposed on edge and preferably having a series of spaced notches 3 on its upper edge and cross wires 4 having loop-like bends 5 therein engaging these cross bars, these cross wires being arranged to engage the bars 2 at points intermediate the recesses 3.

I also provide a center tie unit consisting of a border frame 6 and crossed wires 7 forming a grid-like stretcher, these crossed wires 7 40 being preferably of hard or spring stock and have oppositely disposed offsets 8 at their crossing points so that the wires 7 lie in substantially the same plane.

The body springs 9 are of the helically 45 coiled type and have intermediate coils 10 of

a reduced pitch providing center tie clamping members or coils, so that the springs may be threaded upon the center tie member at its crossing point and rotated to bring these center tie clamping coils into engagement with the center tie wires thereby supporting the springs at intermediate points.

To accomplish this in an effective and rapid way, the bottom coils 11 of the springs are engaged with the center tie wires at their crossing point by hand, as illustrated in Fig. 4. The conical chuck 12 is then introduced into the upper coils of the springs, this being provided with a shank 13 connected to the shaft 14 of the motor 15 which is of such size that it can be readily manipulated. The electrical connections are not illustrated.

This motor rapidly drives the spring downward by rotating it so that in effect a screw action takes place until the stop 16 comes into engagement with the center tie members in which position the bottom coil 11 may be engaged with the crossed members of the base unit at their crossing point, the top coil resting in the notches 3 of the bearing 2 and being engaged under the base wires 4, thereby locking the base wires to the bars 2 and also effectively securing the lower ends of the springs to the base unit.

The springs are thus supported without the necessity for further ties although of course the upper springs may be connected by ties as desired to provide a mattress supporting surface.

My method of assembling springs enables very rapid and uniform assembly thereof.

Having thus described my invention what I claim as new and desire to secure by Letters Patent, is:

1. The method of assembling helically coiled springs having adjacent intermediate coils of reduced pitch providing center tie clamping members with a base unit comprising crossed members and with a center tie unit comprising crossed wires, consisting of

initially engaging the bottom coils of the springs with the crossed wires of the center tie unit at their crossing points, inserting a rotatably driven conical member into the upper ends of the springs whereby they are rotated, bringing their said center tie clamping member coils into engagement with the center tie unit, the said conical member being provided with an adjustable center tie engaging stop at its inner end, and then engaging the bottom coils of the springs with the bottom supporting unit at the crossing points of its members.

2. The method of assembling helically coiled springs having adjacent intermediate coils of reduced pitch providing center tie clamping members with a base unit comprising crossed members and with a center tie unit comprising crossed wires, consisting of initially engaging the bottom coils of the springs with the crossed wires of the center tie unit at their crossing points, inserting a rotatably driven conical member into the upper ends of the springs whereby they are rotated, bringing their said center tie clamping member coils into engagement with the center tie unit, and then engaging the bottom coils of the springs with the bottom supporting unit at the crossing points of its members.

3. The method of assembling helically coiled springs having adjacent intermediate coils of reduced pitch providing center tie clamping members with a base unit comprising crossed members and with a center tie unit comprising crossed wires having opposite offsets at their crossing points, consisting of initially engaging the bottom coils of the springs with the crossed wires of the center tie unit at their crossing points, inserting a rotatably driven conical member into the upper ends of the springs whereby they are rotated, bringing their said center tie clamping member coils into engagement with the center tie unit, and then engaging the bottom coils of the springs with the bottom supporting unit at the crossing points of its members.

4. The method of assembling helically coiled springs having adjacent intermediate coils of reduced pitch with a base unit comprising crossed members and with a center tie unit comprising crossed wires, consisting of initially engaging the bottom coils of the springs with the crossed wires of the center tie unit, rotating the springs by means of a rotatably driven chuck member inserted in their upper ends, said chuck member being provided with a center tie engaging stop at its inner end, and engaging the bottom coils of the spring with the bottom supporting unit at the crossing points of its members.

5. The method of assembling helically coiled springs with a base unit comprising

crossed members and with a center tie unit comprising crossed wires, consisting of initially engaging the bottom coils of the springs with the crossed wires of the center tie unit, rotating the springs by means of a rotatably driven chuck member inserted in their upper ends, and engaging the bottom coils of the springs with the bottom supporting unit at the crossing points of its members.

6. The method of assembling helically coiled springs with a base unit and a central tie unit comprising crossed wires consisting of initially engaging the bottom coils of the springs with the crossed wires of the center tie unit, rotating the springs by means of a driven chuck to bring their lower ends into position to be secured to the base unit, and securing to the base unit.

7. The method of assembling helically coiled springs having adjacent intermediate coils of reduced pitch providing center tie clamping coils with a center tie unit comprising crossed wires having opposite offsets at their crossing points, consisting of initially engaging the bottom coils of the body springs with the crossed wires of the center tie unit at their crossing points, and inserting a rotatable driven conical chuck member into the upper ends of the body springs and thereby rotating them until their said center tie clamping coils are brought into engagement with the center tie unit, the said conical chuck member being provided with a center tie engaging stop at its inner end.

8. The method of assembling helically coiled springs with a center tie unit comprising crossed wires having opposite offsets at their crossing points, consisting of initially engaging the bottom coils of the body springs with the crossed wires of the center tie unit at their crossing points, and inserting a rotatable driven chuck member into the upper ends of the body springs and thereby rotating them until their said center tie clamping coils are brought into engagement with the center tie unit.

9. The method of assembling helically coiled body springs having adjacent intermediate coils of reduced pitch providing center tie engaging coils with a center tie unit comprising crossed wires consisting of first engaging the bottom coils of the springs with the crossed wires of the center tie unit at their crossing points, and then inserting a rotatably driven chuck member into the ends of the springs.

10. The method of assembling helically coiled body springs with a center tie unit comprising crossed wires consisting of first engaging the bottom coils of the springs with the crossed wires of the center tie unit at their crossing points, and then inserting a

rotatably driven chuck member into the ends of the springs.

11. The method of assembling helically coiled body springs with a center tie unit comprising crossed wires consisting of first engaging the bottom coils of the springs with the crossed wires of the center tie unit at their crossing points, and then inserting a rotatably driven chuck member into the ends 10 of the springs, said chuck member having a center tie engaging stop.

In witness whereof I have hereunto set my hand.

GEORGE A. STACKHOUSE.
